ADJUSTABLE IRONING BOARD

John Ripley Kiel, Wilmette, Ill.

Application October 6, 1948, Serial No. 53,037

9 Claims. (Cl. 38—121)

1

This invention has to do with ironing boards of the vertically adjustable type.

The principal object of the invention is to provide, in an ironing board of the type described, a supporting leg structure of new and improved construction, arrangement and operation, which leg structure is expansible from a collapsed position against the underside of the board to a partially or fully extended position beneath the board, thereby enabling the board to be set up at whatever height is most convenient to the user in either a standing or sitting position.

Other objects and advantages of the invention will be apparent to those skilled in the art upon a full understanding of the construction, arrangement and operation of the new leg structure.

One embodiment of the invention is presented herein by way of exemplification but it will be evident that the invention is susceptible of incorporation in various other structurally modified forms coming equally within the scope of the appended claims.

In the accompanying drawings:

Fig. 1 is a side view of an ironing board equipped with a leg structure constructed in accordance with the invention, showing the leg structure in a more or less fully extended or "stand-up" position;

Fig. 2 is a bottom plan view of the board, with the leg structure in the extended position shown in Fig. 1;

Fig. 3 is a side view of the board, showing the leg structure in a but partially extended or "sit-down" position;

Fig. 4 is a bottom plan view of the board and leg structure, in the position shown in Fig. 3;

Fig. 5 is another bottom plan view, showing the leg structure fully collapsed against the underside of the board;

Fig. 6 is a front end view of the board, with the leg structure more or less fully extended as shown in Fig. 1;

Fig. 7 is a corresponding rear end view;

Fig. 8 is a front end view of the board with the leg structure but partially extended as shown in Fig. 3;

Fig. 9 is a corresponding rear end view;

Fig. 10 is a vertical longitudinal section through the front leg;

Fig. 11 is an enlarged fragmentary section through the lower end of the front leg, taken on approximately the line 11—11 of Fig. 10;

Fig. 12 is an enlarged fragmentary vertical section through an intermediate portion of the front leg, at the location of the releasable clutch mem-

2

bers which control the paying out of the tie members connecting the lower end of the front leg with the lower ends of the side legs;

Fig. 13 is a fragmentary horizontal section through the above mentioned clutch members, taken on approximately the line 13—13 of Fig. 12;

Fig. 14 is a transverse section showing such clutch members, taken on approximately the line 14—14 of Fig. 12;

Fig. 15 is a bottom plan view of the operating mechanism mounted on the underside of the board;

Fig. 16 is an enlarged fragmentary vertical section through the device for automatically preventing the leg structure from fully collapsing except in an up-ended position of the board;

Fig. 17 is a fragmentary bottom plan view of the manually releasable rack and pawl device for holding the leg structure in any desired position of adjustment; and

Fig. 18 is a section through the tube which pivotally connects the three crossed legs intermediate their ends.

Referring in detail to the drawings, the new leg structure which constitutes the subject matter of the invention is shown applied to the underside of an ironing board 10. The board 10 may be of conventional design or of any other design, and may, if desired, be provided about its periphery with a short downwardly extending flange or apron, of sufficient depth to more or less completely house the leg structure in the fully collapsed position of the latter. This flange feature, however, is purely optional and has been omitted from the drawings in order to permit illustration of those parts which might otherwise be concealed in certain of the views.

The new leg structure is extensible from a collapsed position against the underside of the board to a partially or fully extended supporting position beneath the board, and is characterized primarily by an inclined front leg 11 which is centered with respect to the board and extends longitudinally thereof, and a pair of laterally offset oppositely inclined rear legs 12 which are disposed at opposite sides of the front leg in medially crossed relation to the latter.

The lower end of the front leg 11 is connected to the lower ends of the side legs 12 by tie members 13. These tie members, which will subsequently be described in more detail, are adapted to extend along the floor between the ends of the legs when the leg structure is extended into a supporting position.

The front leg 11 is preferably of tubular metal

construction and the upper end of the same is hinged on a transverse pivot 14 to a bracket 15 which is secured to the underside of the board at the rear end of the latter. The bracket 15 is of substantial width to afford stability and is hinged to a plate 16 of generally triangular form which is in turn rigidly secured to the leg 11.

The side legs 12, which are similarly of tubular metal construction, are hinged at their upper ends to individual brackets 17, which brackets are both slidably mounted for movement in arcuate paths on a plate 18. The plate 18 is in turn slidably mounted on a longitudinally extending track member 19. The track member 19 is of downwardly opening channel formation, and is fixedly secured to the underside of the board along the center line of the latter. The sliding connections between the plate 18 and the brackets 17 consist of studs 20 on the brackets 17, which extend through and operate in symmetrically arranged arcuate slots 21 in the plate 18.

In the collapsed position of the leg structure the plate 18 assumes a position at the front end of the track member 19, and the hinged and slidably mounted upper ends of the side legs 12 assume spread apart positions at the front ends of the arcuate slots 21, all as shown in Fig. 5.

The side legs 12 are curved preferably from end to end, as shown, and are pivotally connected intermediate their ends to the ends of a cross rod 22, which rod also provides a pivotal mounting for the front leg 11 at the point where the legs cross each other. The side legs 12 are also connected, at points intermediate their lower ends and the cross rod 22, with an extensible and contractable cross brace 23, which brace is of collapsible link formation and consists of two side links 24 which are pivotally connected with the side legs 12 and a medially offset center link 25 which is pivotally connected with the side links 24. The links 24 and 25 are extended or collapsed by means of two rods 26, which rods are pivotally connected at their rear ends to the pivotal connections between the links and are pivotally connected at their front ends to downturned ears 27 on the plate 18.

In the collapsed position of the leg structure the plate 18 is locked against longitudinal sliding movement along the track member 19 by a detent member 28, which member is pivotally secured to the plate 18 at 29 and is provided with a locking finger 30 which extends laterally into a recess 31 in one side of the track member 19, the detent member 28 being urged into its locked position by a spring 32.

During the first part of the movement of the leg structure from its fully collapsed position the temporarily locked plate 18 will act through the rods 26 and links 24 and 25 to progressively spread apart the lower ends of the side legs 12, while the arcuately slidable connections between the plate 18 and the brackets 17 to which the upper ends of the side legs 12 are hinged will cause the upper ends of such legs to converge rearwardly, thereby further spreading apart the lower ends of the side legs 12.

When the leg structure in being extended reaches a position which corresponds to the lowest "sit-down" position of the board, a dowel member 33 on one of the side leg brackets 17 will enter a complementary socket 34 formed in the other side leg bracket, thereby in effect locking the upper ends of the side legs 12 rigidly together in side-wise abutment. At the same time a hook 35 on the front end of one of the side leg brackets 17

will engage with a lip 36 on the rear end of the detent member 28, swinging the detent member 28 far enough away from the track member 19 to disengage the finger 30 against the action of the spring 32. This engagement of the hook 35 with the lip 36 on the detent member 28 will effectively couple up the plate 18 with the laterally abutting upper ends of the side legs 12, through the anchorage provided by the pivotal connection of the detent member 28 with the plate 18, with the result that further extension of the leg support will cause the plate 18 to travel rearwardly along the track member 19.

At about the same time that the hook 35 engages and pulls the lip 36 the studs 20 in the arcuate slots 21 come into abutment with the rear ends 37 of the slots, thereby additionally anchoring the plate 18 to the upper ends of the side legs 12.

20 A brace rod 38 is positioned directly above the front leg 11. In all extended positions of the leg structure the rod 38 is inclined downwardly and forwardly at a more abrupt angle than the underlying front leg 11. The rod 38 is preferably of 25 downwardly opening channel formation in order to nest throughout its length with the front leg 11 in the collapsed position of the leg structure. The lower end of the rod 38 is pivotally connected at 39 to the lower portion of the front leg 11, while the upper end of the rod 38 is pivotally connected at 40 to a bracket 41 which is slidably mounted on the track member 19 behind the plate 18. The bracket 41 is of downwardly opening U-shaped formation, and has a short lever 35 42 pivotally attached to one side of the same at 43. One end of the lever 42 is provided with a laterally extending hook 44 which is adapted upon rearward movement of the bracket 41 into the lowermost position of adjustment of the board 40 to ride upwardly into and lock with a one-way limiting notch 45 in one of the side flanges of the track 19. The other end of the lever 42 is provided with a weight 46, which weight acts to move the hook 44 into the notch 45 when the 45 board is disposed in any generally horizontal position, while acting to automatically release the hook from the notch and permit further rearward travel of the bracket 41 when the board is upended ready for complete collapsing of the leg structure.

50 The two members which are adapted to travel longitudinally of the track 19—namely, the plate 18 which carries the upper ends of the side legs 12 and the bracket 41 which carries the upper end 55 of the brace rod 38—are secured against withdrawal from the track by having portions thereof disposed between the track and the underside of the board, the track being spaced slightly from the surface of the board for this purpose by a plurality of longitudinally separated spacers 47. The plate 18 is prevented from turning at an angle to the track by downturned lugs 48 on the front and rear edges of the plate, which lugs bear against the side flanges of the track, while the 60 bracket 41 is prevented from turning by reason of its nested association with the track.

When the structure starts to open up from its collapsed position, the bracket 41, which will then be in its rear-most position on the track 19, will start moving forwardly along the track. As soon as the leg structure has been extended to a position corresponding to the lowest "sit-down" adjustment, the board can be tilted over onto the leg structure, from its upended storage position into a horizontal position. When the 75

leg structure is opened up beyond the above described lowermost "sit-down" position—which operation can be performed either when the board is in a horizontal position or in an upended position—the bracket 41 will continue its forward movement along the track 19 and the plate 18 will at the same time start moving rearwardly along the track, the bracket 41 and the plate 18 approaching each other until, in the fully extended position of the leg structure, they both move into abutment with one of the intervening spacers 47.

Vertical adjustment of the board is controlled by a hand lever 49, which lever is mounted on the underside of the board in a position generally crosswise of the latter, with one end of the lever conveniently accessible from beneath one side of the board and the other end conveniently accessible from beneath the other side. The lever 49 is movable between a release position, wherein it is crosswise of the board, to a locking position wherein it is disposed at a substantial angle.

The lever 49 is pivotally attached at 50 to the underside of the front end of a flat elongated casing 51, which casing extends rearwardly beyond the track 19 in alignment with the latter. At the location of the lever 49 the casing 51 contains two laterally spring pressed pawls 52 which are pivoted at 53 to the casing. The pawls 52 are provided near their ends with oppositely facing one-way teeth 54 which are adapted to engage with series of one-way teeth 55 on two longitudinally extending rack bars 56 and 57. The pawls 52 are provided beyond the teeth 54 with ears 58 which are adapted to be engaged by upturned lugs 59 on the lever 49. When the lever is turned from its angular locking position with respect to the board to its crosswise release position the lugs 59 on the lever 49 will withdraw the pawls 52 from engagement with the rack bars 56 and 57, thereby freeing the rack bars and permitting the latter to move longitudinally within the casing 51.

The rack bar 56—which can move rearwardly at all times with respect to its pawl 52 but can only move forwardly when the control lever 49 is swung into its release position—extends forwardly through the front end of the casing 51 adjacent one side of the latter and is pivotally connected at the stud 20 to one of the brackets 17 which carry the upper ends of the side legs 12. The other rack bar 57—which can only move rearwardly when the control lever 49 is in its release position but can move forwardly at all times—likewise extends forwardly through the front end of the casing 51 adjacent the other side of the latter, and is connected at its front end to the bracket 41 which carries the upper end of the brace rod 38.

The rack bar 56 is provided intermediate its ends with a slot 60 into which one end of the lever 42 is adapted to move when the hook 44 on that lever moves into the notch 45. This engagement of the end of the lever 42 with the slot 60 anchors the rack bar 56, and consequently the plate 18 to which the rack bar is connected, against forward movement until such time as the board has been upended preparatory to collapsing the leg structure.

It will be understood from the foregoing that when the control lever 49 is in its release position the board can be moved upwardly or downwardly, with a corresponding contraction or extension of the leg structure, whereas when the

control lever is in its locking position the board is prevented from being lowered, with attendant contraction of the leg structure, but can be raised with ease into any desired higher position of adjustment, with an attendant extension of the leg structure.

To lower the board to any extent desired it is merely necessary to swing the lever 49 into its release position, whereupon the board will sink gradually under its own weight, stopping when the lever is moved to its locking position. The lever 49 is biased at all times toward its locking position by a small tensioned coil spring 61, which spring extends from a portion of the lever to a portion of the casing 51. Movement of the lever 49 into its release position will only permit the board, however, to lower to its lowest "sit-down" position of adjustment, as at that point the hook 44 on the weighted lever 42 will ride into the notch 45 in the track 19, automatically preventing further downward movement of the board until such time as the board is upended for storage, at which time the hook 44 will disengage from the notch 45, permitting full collapse of the leg structure.

In order to maintain the control lever 49 in release position when the leg structure is fully collapsed, for a purpose which will hereinafter be described, the bracket 41 which carries the upper end of the brace rod 38 is provided with a rearwardly extending finger 62, which finger is adapted to move into abutment with one side of the control lever 49 in the fully collapsed position of the leg structure.

After the leg structure in being opened up has been extended to what corresponds to the lowest "sit-down" position, the control lever 49 will be automatically returned from its release position to its locking position by means of a longitudinally extending rod 63 which is secured at its front end to the plate 18 and extends through an apertured ear 64 on the control lever 49 in frictional engagement with a small leaf spring 65 on the lever. As soon as the plate 18 starts to move rearwardly, in extending the leg structure from its lowermost "sit-down" position, the frictional engagement of the spring 65 against the then rearwardly moving rod 63 will swing the control lever 49 from a more or less dead center position of the coil spring 61 into a locking position.

The previously mentioned tie members 13 between the lower end of the front leg 11 and the lower ends of the side legs 12—which keep the legs from spreading apart after the board has been adjusted to any particular height—preferably consist in part of small diameter rods 66 which are pivotally secured at their rear ends to the lower ends of the side legs 12. Near their front ends the rods 66 are connected to flexible chains 67, which chains continue forwardly to the lower end of the front leg 11 and pass alongside each other about juxtaposed rollers 68 which are journaled in the end of the leg at that point. The rollers 68 and the portions of the chains extending about the same are partially housed within a small sheet metal shield 69 which is pivotally attached to the leg on the axis of the rollers and affords an angularly adjustable supporting foot for the leg.

From the rollers 68 the chains 67 extend lengthwise for some distance within the front leg 11 and connect with the ends of two clutch rods 70 housed within the leg. At their point of connection with the clutch rods 70 the chains 67 are

connected with two equalizing coil springs 71, which springs in turn converge into connection with a single main coil spring 72. The main spring 72 continues lengthwise of the front leg 11 and is connected at its far end under tension to the rear end of the leg. The springs 71 and 72 act to keep both tie members 13 reasonably taut at all times, in the collapsed as well as extended position of the leg structure, and may even serve, if desired, to partially or wholly counterbalance the weight of the board during lowering of the same.

The clutch rods 70 pass freely through closely fitting apertures 73 in two segmental clutch members 74. The members 74 are of semicircular form and are held together loosely in complementary relation by a spring clip 74a to provide in effect a two-part disk 75. The disk 75 fits loosely within the leg 11 and is capable of tilting therein into a position wherein its two parts will individually bind against and grip the rods 70. The disk 75 is cut away at one point between the segments 74 to pass the main spring 72, and is apertured at another point between the segments to pass a trip rod 76. A small cross bar 77 is secured on the trip rod 76 beyond the disk 75, and small coil springs 78 are compressed between the cross bar 77 and the segments 74 for individually tilting the same into binding engagement with their respective clutch rods 70. The trip rod 76 is provided at its front end with a head 79, which head is adapted to draw the segments 74 back from their tilted positions when the rod is drawn rearwardly, whereby to release both clutch rods 70 and permit paying out of the chains 67 and rods 66.

While the tie members 13 have been illustrated and described as of composite rod and chain construction, they could be formed entirely as chains or other flexible connectors. They are preferably so arranged as to rest flatly on the floor but they might instead be elevated somewhat without loss of their tying function.

The rear end of the trip rod 76 emerges from the rear end of the front leg 11 and is connected to the rear end of a link 80 which extends longitudinally of the casing 51 adjacent the underside of the latter. The front end of the link 80 is pivotally connected at 81 in an off-center position to the control lever 49. As a result, when the lever 49 is moved into its release position the tie members 13 will be released, and when the lever 49 is moved to its locking position the tie members 13 will be locked.

In order to prevent the tie members 13 from being locked when the leg structure is being fully collapsed, the control lever 49 is caused to assume its release position by being engaged at such time by the previously described finger 62 on the bracket 4.

The previously described cross rod 22—which forms a pivotal connection between the front leg 11 and side legs 12—may be constructed and connected with the legs in any desired manner, but is herein disclosed as a tube 82 which passes loosely through apertures in the front leg and is arranged with its ends seated in apertures in the side legs. The tube 82 is fixedly pinned to the front leg 11, is universally mounted in the side legs 12 whereby to permit limited endwise as well as angular movement of the tube in the apertures and thus avoid binding during the erection of the legs, and is retained in the apertures in the side legs by a bowed spring member 83 within the tube having projecting right angularly bent

ends 84, which ends releasably engage with the inner walls of the side legs at the ends of the tube 82.

When the leg structure is fully collapsed against the underside of the board the leg structure may be releasably locked in such collapsed position by means of a spring latch 85 of any suitable character located on the underside of the front end of the board adjacent the end of the front leg 11. The latch is provided with a detent 86 which springs into the hollow front end of the leg, latching the latter against withdrawal. To unlock the front leg and consequently the entire leg structure from its collapsed position, it is merely necessary to press back the latch 85.

Briefly summarizing the way in which the new leg structure is adapted to be collapsed, extended and adjusted, and starting with the board resting in an upended position on its rear end, with the leg structure fully and compactly collapsed against the underside of the board within the margins of the latter, and with the control lever 49 in its released position it is merely necessary in order to extend the leg structure for one to grasp the then upwardly projecting end of the front leg 11 and swing it outwardly and downwardly in an arc away from the board, first, of course, releasing the latch 85, if the board is equipped with a latch.

This movement of the front leg 11 will automatically cause the lower ends of the side legs 12 to swing outwardly and the upper ends of such legs to shift downwardly on the then stationary plate 18, converging at the same time into laterally abutting longitudinally locked engagement with each other.

During this movement of the front leg 11 and side legs 12 the end of the brace rod 38 which is pivoted to the front leg 11 will swing outwardly and downwardly with the front leg, and the bracket 41, to which the other end of the brace rod 38 is hinged, will start to move upwardly.

If for any reason it is desired to again fully collapse the leg structure while the latter is still in this semi-collapsed position, the same can be done by merely swinging the projecting end of the front leg 11 upwardly and inwardly again toward the board, whereupon the side legs 12 and the brace rod 38 will again assume their original positions with respect to the front leg 11 of the board. This return can be accomplished without having to operate the control lever 49, the latter having remained in its release position.

At the end of this preliminary extension, the brackets 17 to which the upper ends of the side legs 12 are hinged will come into abutment with the end of the arcuate slots 21 in the plate 13 and the resulting initial downward movement of the plate 18 will immediately act through the rod 63 to swing the control lever 49 past the dead center position of the spring 61 from its release position into its locking position.

After the leg structure has been partially extended in the manner above described, to a position which corresponds to the lowest position in which it is adapted to support the board in use, namely, the lowest "sit-down" adjustment, the board can be tilted over into a horizontal position on the leg structure in readiness for use. Or before tilting the board over the leg structure can, if desired, be further extended, merely by swinging the projecting end of the front leg 11 farther down.

To elevate the board when in any of its opera-

tive positions, it is merely necessary to grasp the sides of the board and lift it to the desired position. In doing this it is not necessary to move the control lever 49 into its release position as the ratchet action of the pawls 52 will permit free movement of the rack bars 53 and 57, the rack bar 56 forwardly and the rack bar 57 rearwardly.

To lower the board from one position to another it is merely necessary to move the control lever 49 into its release position and hold it there against the action of the spring 61 until the board has settled to the desired elevation.

To close up the board after use, the board is suspended, the control lever 49 is moved and held in its release position, and the projecting end of the front leg 11 is grasped and swung upwardly and inwardly toward the board until the leg structure has moved into its fully collapsed position.

While the centered longitudinally extending leg 11 has been described as the "front" leg and the side legs 12 as the "rear" legs, it will, of course, be appreciated that these terms are only relative and that if desired the arrangement of the legs might be reversed end for end with respect to the front and rear ends of the board. It will also be appreciated that the new leg structure might be used for adjustably supporting members other than ironing boards.

I claim:

1. In an ironing board of the adjustable stand-up or sit-down type, a leg structure which is extensible from a collapsed position against the under side of the board to a partially or fully extended supporting position beneath the board, said leg structure including an inclined front leg and a pair of oppositely inclined rear legs, the front leg being centered with respect to the longitudinal axis of the board, and the rear legs being disposed at opposite sides of the center line of the board in crossed relation to the front leg, tie members extending between the spaced apart lower ends of the rear legs and the lower end of the front leg, said tie members provided with flexible extensions which continue upwardly from the lower end of the front leg, and anchored spring means connected under tension with said extensions for eliminating slack in said tie members.

2. In an ironing board of the adjustable stand-up or sit-down type, a leg structure which is extensible from a collapsed position against the under side of the board to a partially or fully extended supporting position beneath the board, said leg structure including an inclined front leg and a pair of oppositely inclined rear legs, the front leg being centered with respect to the longitudinal axis of the board, and the rear legs being disposed at opposite sides of the center line of the board in crossed relation to the front leg, tie members extending between the spaced apart lower ends of the rear legs and the lower end of the front leg, said tie members provided with flexible extensions which continue upwardly from the lower end of the front leg, a spring member which is anchored at one end and is connected under tension at its other end with said extensions for eliminating slack in said tie members, and a manually controlled clutch associated with said tie members for determining the effective length of the same between the leg ends.

3. In an ironing board of the adjustable stand-up or sit-down type, a leg structure which is extensible from a collapsed position against the under side of the board to a partially or fully ex-

tended supporting position beneath the board, said leg structure including an inclined front leg and a pair of oppositely inclined rear legs, the front leg being centered with respect to the longitudinal axis of the board, and the rear legs being disposed at opposite sides of the center line of the board in crossed relation to the front leg, tie members extending between the spaced apart lower ends of the rear legs and the lower end of the front leg, said tie members provided with flexible extensions which continue upwardly from the lower end of the front leg, a spring member which is anchored at one end and is connected under tension at its other end with said extensions for eliminating slack in said tie members, a manually controlled clutch associated with said tie members for determining the effective length of the same between the leg ends, and means mounted on the under side of the board for manually controlling said clutch.

4. In an ironing board, a leg structure which is extensible from a collapsed position against the under side of the board to an extended position beneath the board, said leg structure including an inclined leg which is centered with respect to the board and extends longitudinally thereof, and a pair of laterally offset oppositely inclined legs which are disposed at opposite sides of the center leg in crossed relation to the latter, a pivotal connection between the center and side legs at the point where they cross, a pivotal connection between the upper end of the center leg and the board, a longitudinally slid able connection between the upper ends of the side legs and the board, an inclined brace rod positioned above the center leg between the side legs in crossed relation to the latter, a pivotal connection between the lower end of the rod and the lower ends of the center leg, and a longitudinally slid able connection between the upper end of the rod and the board, said first and second mentioned longitudinally slid able connections moving in opposite directions to each other both during collapse of the leg structure and during extension of the same.

5. In an ironing board, a leg structure which is extensible from a collapsed position against the under side of the board to an extended position beneath the board, said leg structure including an inclined leg which is centered with respect to the board and extends longitudinally thereof, and a pair of laterally offset oppositely inclined legs which are disposed at opposite sides of the center leg in crossed relation to the latter, a cross member pivotally connected with each of the side legs intermediate their ends, means for moving the upper ends of the side legs toward and away from each other whereby to bring the lower ends of said legs closer together when the support is collapsed and farther apart when the support is extended, and a laterally releasable locking connection between the upper ends of the side legs for securing the same together for movement only as a unit lengthwise of the board after said upper ends are moved toward each other.

6. In an ironing board, a leg structure which is extensible from a collapsed position against the under side of the board to an extended position beneath the board, said leg structure including an inclined leg which is centered with respect to the board and extends longitudinally thereof, and a pair of laterally offset oppositely inclined legs which are disposed at opposite sides of the center leg in crossed relation to the latter, a cross

member pivotally connected with each of the side legs intermediate their ends, guide means connected with the underside of the board in guiding engagement with the upper ends of the side legs above said cross member for moving the upper ends of the side legs toward and away from each other whereby to bring the lower ends of said legs closer together when the support is collapsed and farther apart when the support is extended, a laterally extensible and contractible cross brace between the side legs intermediate the lower ends of the latter and said cross member, and means for automatically extending the cross brace when the upper ends of the side legs are moved toward each other.

7. In an ironing board, a leg structure which is extensible from a collapsed position against the under side of the board to an extended position beneath the board, said leg structure including an inclined leg which is centered with respect to the board and extends longitudinally thereof, and a pair of laterally offset oppositely inclined legs which are disposed at opposite sides of the center leg in crossed relation to the latter, a cross member pivotally connected with each of the side legs intermediate their ends, guide means connected with the underside of the board in guiding engagement with the upper ends of the side legs above said cross member for moving the upper ends of the side legs toward and away from each other whereby to bring the lower ends of said legs closer together when the support is collapsed and farther apart when the support is extended, a laterally extensible and contractible cross brace between the side legs intermediate the lower ends of the latter and said cross member, and means for automatically extending the cross brace when the upper ends of the side legs are moved toward each other, said cross brace comprising two side links pivotally connected to the side legs and a center link pivotally connected to the side links, and said brace extending means including a push and pull rod which is anchored at one end and is connected at its other end to said cross brace.

8. In an ironing board, a leg structure which

is extensible from a collapsed position against the under side of the board to an extended position beneath the board, said leg structure including an inclined leg which is centered with respect to the board and extends longitudinally thereof, and a pair of laterally offset oppositely inclined legs which are disposed at opposite sides of the center leg in crossed relation to the latter, and an inclined brace rod above the center leg pivotally connected at its lower end with the latter and slidably connected at its upper end with the board, said rod being of downwardly opening channel construction and of such size as to nest with the leg in the collapsed position of the leg structure.

9. In an ironing board, a leg structure which is extensible from a collapsed position against the under side of the board to an extended position beneath the board, said leg structure including an inclined leg which is centered with respect to the board and extends longitudinally thereof, and a pair of laterally offset oppositely inclined legs which are disposed at opposite sides of the center leg in crossed relation to the latter, a cross member pivotally connected with each of the side legs intermediate their ends, the upper ends of the legs being connected with the board and the upper ends of the side legs being shiftable longitudinally of the board, means for locking said ends against shifting, tie members extending between the front leg and the rear legs below said cross member, said tie members being extensible in the direction of their length, means for locking said tie members against extension, and single manually operable control means for simultaneously releasing both of said locking means.
